DESIGN FOR A FISH BAIT

Thomas A. Findlay, Minocqua, Wis.

Application May 3, 1946, Serial No. 129,301

Term of patent 14 years

(Cl. D31—4)

To all whom it may concern:

Be it known that I, Thomas A. Findlay, a citizen of the United States, residing at Minocqua, in the county of Oneida and State of Wisconsin, have invented a new, original, and ornamental Design for a Fish Bait, of which the following is a specification, reference being had to the accompanying drawing, forming a part thereof, in which:

Fig. 1 is a top plan view of a fish bait, showing my new design;

Fig. 2 is a side elevational view thereof;

Fig. 3 is a bottom plan view thereof;

Fig. 4 is a rear elevational view thereof; and

Fig. 5 is a front elevational view thereof.

I claim:

The ornamental design for a fish bait, as shown.

THOMAS A. FINDLAY.
